UNITED STATES PATENT OFFICE.

NICHOLAS SANDOR, OF DRESDEN, GERMANY.

EGG CRATE.

Application filed October 28, 1921. Serial No. 511,212.

To all whom it may concern:

Be it known that I, NICHOLAS SANDOR, a citizen of the Republic of Hungary, residing at Dresden, Saxony, Germany, have invented certain new and useful Improvements in Egg Crates; and I do hereby declare the following to be a full, clear, and exact description of the same, reference being had to the accompanying drawings, forming part 10 of this specification.

This invention relates to a packing for eggs or similar articles, particularly that form of packing which utilizes cell forming partitions lying at right angles to one another and interlocking. In the usual form of packing each layer is formed of two series of partitions, the floors of each tier being formed by a sheet of material the entire length and width of the container. The 20 present invention contemplates the omission of the sheet material separating the tiers, forming egg-supporting seats in each layer on which seats are supported the eggs of the tiers above, each seat in the tier below being 25 located at the center of the tier above.

A particular object of the present invention is the formation of the partition itself, each of these partitions being similar and being formed of a material forming a 30 hollow rectangle in cross section so that each partition is double walled, this construction greatly increasing the elasticity of the walls and consequently reducing the breakage of eggs.

A further object of the present invention is the provision of egg seats laterally extending on either side of one of the narrower surfaces of the partition, each lateral extension being of such length as to overlie the 40 corresponding narrow section of each partition of the co-operating series, that is, the series which lies at right angles to the series of parallel partitions having egg-receiving seats. The egg-receiving seats are in consequence of this construction supported by each pair of co-operating partitions, the 45 seats being integral with one partition and resting upon the partition at right angles. In order to further increase the factor of 50 safety the small resilient tongues extending from the co-operating partition underlie the elliptical egg-receiving seat and consequently add to its strength. It has been found in practice that with this double wall 55 construction with its interlocking egg-receiving seats that an egg is practically never

broken by a jar or blow parallel to its longitudinal axis and that by virtue of the double wall partition the eggs toward the middle of the container cannot be broken by a jar 60 parallel to a lateral axis of the egg.

A further object of the present invention lies in the provision of partitions having equi-distant egg-receiving seats in which the distance from one end of the partition 65 to the nearest seat is very materially in excess of the distance from the other end to the nearest egg-receiving seat. The purpose of this is to permit the use of a single type of partition which by being reversed 70 may form the staggered tier above.

While there are a great many advantages obtained by staggering the partition walls so that the junction of the tier below lies in the center of the cell in the tiers above, it 75 may sometimes be preferred to have all of the eggs in the same vertical line as is at present the custom. This is taken care of in a modification of the present invention by having each alternate tier of relatively small 80 size and serving merely to separate the egg-holding tiers.

In the drawings are shown two embodiments of my invention.

Figure 1 is a plan view of a container 85 fitted with partitions made in accordance with my invention in its preferred form.

Fig. 2 is a plan view of the blank for a section of a partition before it is bent into form.

Fig. 3 is a perspective of a portion of a partition.

Fig. 4 is a vertical section through the container showing the eggs in position.

Fig. 5 is a side view of a single partition. 95

Fig. 6 is a top plan view of a joint formed by two partitions.

Fig. 7 is a section taken on line 7—7 of Fig. 5.

Fig. 8 is a modification utilizing alternate 100 series of slight height, merely separating the tiers, and not containing eggs.

As will be seen from Fig. 1 which illustrates a rectangular box or container 10 the partition strips cross each other at right 105 angles interlocking in the usual and customary way in this art. The walls of the partitions are, however, double, the partitions being made of paper, card board, or any other similar substance preferably cut 110 from a single sheet. It will be understood that while I have shown the partition walls

in all of the views in the preferred form with egg seats I do not wish to be limited to this form and contemplate as my invention the provision of hollow partitions having double side walls and staggered in adjacent tiers so that each junction in the tier below lies in the center in the rectangular cell in the tier above.

Referring particularly to Fig. 2, partitions are formed of a single sheet of material creased or scored as shown by the dotted lines and cut as shown by the full lines. The scores 15 and 16 form the margin of what is termed throughout the specification and claims as the bottom wall 17, although it is obvious that in each layer the bottom wall of one series is the top wall of the series at right angles thereto. The term, however, is very convenient and it is possible to describe the structure with greater exactness by the use of this possible incorrect term. The adjacent semi-circular cuts 19 and 20 form the lateral extensions 21 of the elliptical egg-receiving seats 22 at the same time forming an arch 23 in each of the side walls.

The scores 25 and 26 form the margin of the so-called top wall 27 which is not unbroken as is the bottom wall 17, but is severed by the cuts 28 forming resilient tongues 29. The small segmental sections 30 are entirely removed by the curved cuts 31 and the straight cuts 32 co-linear with the scores 25 and 26, thus forming arches 37. The cuts 33 and 34 together with the score 35 form flaps 36 and corresponding slots 42. By making the score 35 a cut the flaps 36 may be entirely removed as are the segmental sections 30, this being purely a matter of choice, but I find it preferable to use the score 35 and to bend back the flap 36 to form a slight additional strengthening rib between the adjacent side walls 38 and 39, the latter being formed by gluing the margin 40 to the margin 41, the short edge of the flaps 36 serving as a limit and guide in pasting.

In assembling, the partitions of one series are arranged parallel to each other and with the so-called bottom side down, the lateral extensions 21 affording ample surface to maintain the partitions in a standing position. The partitions of the co-operating series are now placed over the first series and are pressed down upon them with the four tongues in contact. The tongues are resilient and readily give to permit passage of the double walls so that the partitions of one series fit within the slots formed by the score 35 and cuts 33 and 34, the cut 33 being mid-way between the top and bottom scores 25 and 16. Upon being assembled the tongues 29, due to their inherent resilience, snap back into place underlying the egg-receiving seats 22 in each case and serving to support the same.

All the various layers may be assembled at one time and then it will only be necessary to reverse each alternate layer for the cells to be properly staggered to bring a seat in the center of the cell above and below. It will be noted that an arch is formed at each end of each junction and it also should be noted that the lateral extensions 21 on the seats are of such overhang as to extend an appreciable distance beyond the inner end of the tongue 29 so as to rest firmly upon the so-called top wall 27. It will thus be seen that the egg-receiving seats 22 would be afforded support at either side even in the absence of the tongue 29, the latter, however, do aid, are found convenient and require no extra cost.

In the modification shown in Fig. 8 the egg containing layers are exactly as described but each alternate tier 44 is composed of crossed interlocking partitions 45 of but slight height serving merely to support eggs above and below and permitting the storing of the eggs in vertical alinement.

What I claim is:

1. A cell-forming partition adapted to cooperate with other exactly similar partitions to form a plurality of cells each partition consisting of a pair of parallel side walls with integral top and bottom walls, said bottom wall being unbroken throughout the length of the partition.

2. A cell-forming partition consisting of a pair of parallel side walls with integral top and bottom walls, said bottom wall being unbroken throughout the length of the partition, and having a plurality of equi-spaced enlargements.

3. A cell-forming partition consisting of a pair of parallel side walls with integral top and bottom walls, said bottom wall being unbroken throughout the length of the partition, each of said side walls being cut away at regular intervals to form integral equi-spaced enlargements in said bottom wall.

4. A cell-forming partition consisting of a pair of parallel side walls with integral top and bottom walls, said bottom wall being unbroken throughout the length of the partition, and said top wall being continuous throughout the length of the partition but being severed at regular intervals to receive a co-operating partition.

5. A double walled cell-forming partition characterized by the provision of oppositely disposed horizontal lateral base extensions cut from each of the side walls.

6. A plurality of double walled cell-forming partitions each having spaced lateral base extensions forming an egg-receiving seat and having a pair of resilient tongues adapted to underlie each seat when said partitions are assembled.

7. A plurality of tiers of partitions forming square cells, each cell having a plane

egg-receiving seat at each corner thereof, each of said seats forming the support for an egg in the tier above.

8. In an egg crate, a plurality of tiers of interconnected double walled partitions, each partition having a plurality of spaced extensions on one wall and a plurality of opposed tongues on the opposite wall, the tongues on each partition being adapted to contact with and strengthen the spaced extensions of each co-operating partition.

9. An egg crate of the type in which the cell-forming partitions of each tier are staggered so that the eggs of one tier rest on the partitions of the tier below, characterized by the provision of an egg seat at each partition junction, said seats lying in a horizontal plane.

10. An egg crate of the type in which the

cell-forming partitions of each tier are staggered so that the eggs of one tier rest on the partitions of the tier below, characterized by the provision of an egg seat at each partition junction, said seats lying in a horizontal plane and being integral with the parallel partitions of one of the series of each tier.

11. An egg crate of the type in which the cell-forming partitions of each tier are staggered so that the eggs of one tier rest on the partitions of the tier below, characterized by the provision of an egg seat at each partition junction, said seats being integral with the parallel partitions of one of the two series of each tier, and resting upon the partitions of the other series.

NICHOLAS SANDOR.
